UNITED STATES PATENT OFFICE.

FRANK R. WESSA, OF NORWOOD, OHIO.

PROCESS OF TREATING HIDES.

No. 883,124.

Specification of Letters Patent. Patented March 24, 1908.

Application filed March 30, 1907. Serial No. 365,445.

To all whom it may concern:

Be it known that I, FRANK R. WESSA, a citizen of the United States, residing at Norwood, in the county of Hamilton and State 5 of Ohio, have invented certain new and useful Improvements in Processes of Treating Hides, of which the following is a specification.

My invention relates to improvements in 10 process of treating hides in the production of enameled leather.

One of its objects is to provide a process of treatment which will require less space for the treatment of a given quantity of 15 hides.

Another object is to provide a process requiring less labor.

Another object is to provide a process requiring less apparatus and permit the employment of more substantial and permanent 20 apparatus.

Another object is to so arrange the hides in the baking steps as to attain a superior article and also to reduce the oven capacity required.

It further consists in certain details, all of which will be more fully set forth in the description of said process and the accompanying drawings, in which,

Figure 1 is a view of a frame with hide attached, as employed in my improved process. Fig. 2 is a perspective view of a hide ready to be introduced into the oven as shown in Fig. 3. Fig. 3 is a section through 35 an oven showing the hides arranged therein. Fig. 4 is a detail view of one of the clamps employed to attach the hides to the frame Fig. 1.

By my improved process of treatment, 40 frames, D, preferably of metal are permanently located at the points where the hides are to be coated with enamel and stoned. These frames may be set upon their own legs, D', which may be screwed to the floor, 45 if desired. Then by employing metal clips, K such as shown in Fig. 4, for instance, which can be quickly attached to the hides and buttons, knobs, H or similar means for automatically grasping or locking the cords 50 I leading such clips to the frame, after being strained, I am enabled to attach to and detach the hides from the frames more quickly and readily than it has heretofore been possible to transfer the hides and their wooden 55 frames from place to place.

In removing a hide from one of my perma-

nent frames, a pole, or rod, E, is placed beneath the hide and after the clips are released, the hide hangs over the pole, as shown in Fig. 3, and may be thus carried to the baking oven or to another frame for treatment.

In the baking of the hides, the poles are placed side by side upon guides, d, in the ovens, F, and I am enabled thus to place many more hides in an oven of a given size 60 than could be done where the wooden frames were placed in the ovens with the hides attached, thus requiring less oven space. Also, the hides are in better position to attain the desired result, as should there 65 be any tendency of the enamel to flow, it will flow evenly toward the edges of the hide, leaving an even coat over the whole surface, while with hides on the frame, there are pockets, or baggy places toward the center 70 of the hides, and the edges are always higher. Thus any flow would accumulate in these pockets and would be baked at these places into a thicker coat than desired. Also, with the hides suspended on the poles, there is a 75 better circulation in the oven and all parts are evenly and thoroughly baked. As the hides are strained again after each baking step, they can be evenly and tightly drawn upon the frames, and the stoning and recoat- 80 ing can be more effectually done and a better 85 result attained than by the use of a single frame throughout, as with the single frame pockets occur which cannot be readily taken out, and which are objectionable in the sub- 90 sequent baking, stoning and recoating steps.

Having described my process, what I claim is:

1. The process of treating hides comprising the following steps, attaching the hides 95 to frames and applying a coat of enamel, detaching the hides and suspending them in a vertical position in an oven to bake the enamel, removing the hides from the oven attaching them to frames and stoning and 100 re-coating them, then removing them from the frames and suspending them as before in an oven to be baked.

2. The process of treating hides which comprises the use of a series of permanently 105 located frames and consists of the following steps, straining the hides upon the first series of frames and applying a filler coat, detaching the hides from said frames and suspending them side by side upon horizontal bars in an oven and baking said coat 110 thereon, removing said hides and straining

them upon a second series of frames, stoning the hides and then re-coating them while so strained upon the frames, detaching the hides from said second series of frames and suspending them side by side upon horizontal bars in an oven, and baking the last mentioned coat.

3. The process of treating hides which comprises the use of a series of permanently located frames and consists of the following steps, straining the hides upon the first series of frames and applying a filler coat, detaching the hides from said frames and suspending them side by side upon horizontal bars in an oven and baking said coat thereon, removing said hides and straining them upon

a second series of frames, stoning the hides and then re-coating them while so strained upon the frames, detaching the hides from said second series of frames and suspending them side by side upon horizontal bars in an oven, baking the last mentioned coat, and repeating the stoning, re-coating and baking steps as above described until the desired result is attained.

25

In testimony whereof I have affixed my signature in presence of two witnesses.

FRANK R. WEssa.
